CLAIM

The ornamental design for an insect eliminating device, as shown and described.

DESCRIPTION

FIG. 1 is a front view of an insect eliminating device showing our new design;

FIG. 2 is a rear view thereof;

FIG. 3 is a rear perspective view thereof;

FIG. 4 is a front perspective view thereof;

FIG. 5 is a top view thereof;

FIG. 6 is a bottom view thereof;

FIG. 7 is a side view thereof; and,

FIG. 8 is an opposite side view thereof.

The broken lines showing of portions of the insect eliminating device is included for the purpose of illustrating environmental structure and forms no part of the claimed design.
